UNITED STATES PATENT OFFICE.

ALPHONSO T. PALMER, OF CHICAGO, ILLINOIS.

RAIL ANTICREEPER.

Application filed July 29, 1925. Serial No. 46,707.

My invention relates to anti-creeping devices for rail-way rails, and the like, and has for one of its objects the provision of simple and effective means for efficiently and 5 effectively holding railway rails, and the like, from longitudinal movement.

A further object of my invention is the provision of a device of the character mentioned which will not be detached by movement of the rail in frozen ground.

A still further object of my invention is the provision of a device of the character mentioned which can be easily and quickly attached to a railway track.

15 Another object of my invention is the provision of an anti-creeper comprising a single unitary member.

A further object of my invention is the provision of a device of the character mentioned that is adapted to dig into a rail when the latter tends to move longitudinally relative to a tie to which it is spiked.

In the drawings:

Fig. 1 is a top plan view of a railway rail, tie, tie plate and anti-creeping device embodying my invention;

Fig. 2 is a side elevational view of the device disclosed in Fig. 1 showing a sectional view of a railway rail; and

30 Fig. 3 is an end view of the parts shown in Fig. 1.

Referring more particularly to the drawings, I have indicated in Fig. 1 a fragment of a railway tie 4 of any desired construction. On the tie 4 is indicated the bottom portion of the rail 5 having the usual flanges 5'. Disposed under the rail 5 is a resilient member 6. The member 6 may be of a stiff spring metal or of any desired material. It 40 is preferable that it have sufficient stiffness and size to afford strength to hold the anti-creeping parts against the rail flanges to prevent movement thereof along the rail. The member 6 has its central portion curved 45 as shown at 7 in Figs. 1 and 3 so that the curved intermediate portion 7 protrudes outwardly away from the side 8 of the tie 4. The end portions 9 and 10 of the spring plate 6 are substantially flat and the curvature of the spring plate exists between these end portions.

The edge 11 of the curved portion of the spring plate 6 is disposed below the flanges 5' and the flat end portions 9 and 10 extend 55 above such flanges. The flat end portion 9

is provided with a hook 12 which is adapted to engage one of the flanges 5'. A hook 13 is provided on the flat end portion 10 of the spring plate 6. It will be seen in Figs. 1 and 2 that the hooks 12 and 13 extend over the upper surface of the flanges 5' and that the hook 12 is longer than the hook 13 for reasons hereinafter disclosed.

The spring plate 6 is provided with an outwardly directed bulge located at the center of the curved portion 7. It will be seen in Fig. 1 that the outwardly bulged portion 14 has its center of curvature on the same side of the spring plate 6 as is the center of curvature of the curved portion 7. In other words, both the curved portion 7 and the bulged portion 14 are directed away from the side 8 of the tie 4. The bulged portion 14 is substantially spoon-shaped in form and is longer than it is wide. An indentation on the concave side of the curved portion 7 results from the formation of the bulge 14 and this indentation tends to draw or pull the ends of the spring metal plate together. The curvature 7 and the bulge 14 both co-operate in producing a spring action in the plate 6 that tends to impel the end portions of such plate towards each other. A slight extension 15 is provided on the edge 11 of the curved portion 7. This extension extends an equal distance on each side of the center line of the spring metal plate 6 and is provided with a sharp knife edge 16. The knife edge 16 is shown in Fig. 3 to have a vertical side 17 and a bevelled side 18. The bevelled side 18 extends from the upper edge 11 of the curved portion 7 to the knife edge 16. This knife edge has the same curvature as the curvature of the portion 7 of the metal plate 6.

When the anti-creeping device is secured to the rail flanges 5' it is positioned as shown in the dotted lines at 19 with the large hook 12 of the flat portion 9 disposed over one flange 5' of the rail. A tool such as shown in Fig. 2 having a bent lower end 23 and a handle 24 may be employed by inserting the bent end in the opening 25 for the purpose of expanding the spring metal plate 6. The intermediate portion of the handle may be rested against the edge 20 of the left hand flange 5' while a force is applied on the upper end of such handle to move the latter in the direction of the rail. This action will result in a temporary reduction of the

curvature of the plate and may be continued until the plate has been extended sufficiently to permit the hook member 13 to be disposed over the edge 20 of the left hand flange 5'. Use of the tool may then be discontinued so as to permit the tension in the spring plate 6 to force the hook 13 over the upper surface of the left hand flange 5'. The edge portions 20 are then firmly gripped in the slots 21 and 22 beneath the hooks 12 and 13 respectively, all of the forces applied on the edge portions of the rail being supplied by the bulged and curved portion of the spring metal plate.

15 It will be seen in Fig. 3 that the knife edge 16 is at a higher elevation than the edge 11 of the curved portion 7. As a result of the length of the extension 15 the anti-creeping device is caused to assume the position shown in Fig. 3 with the lowermost portion of the flat sides engaging the side 8 of the tie 4. Thus, when the rail tends to move longitudinally relative to the tie 4 it also tends to carry the anti-creeping device which is firmly clamped on the flange thereof along with it. The slightest movement of the rail causes the bottom portion of the flat ends 9 and 10 to press against the side 8 of the tie 4 thus restraining such movement. The pressure against the side of the tie causes the plate to act as a lever to force the edge 16 against the under face of the rail and to bite into the rail to prevent the rail from slipping.

20 30 35 The movement of the rail is restrained in the above-mentioned ways, and the great power of the anchoring device is the result of the leverage action it exerts when the rail tends to move. Even the slightest movement of the rail would cause the spring metal plate 6 to tend to turn about the knife edge 16 as a fulcrum. This tendency of the spring metal plate 6 causes the knife edge to bite into the rail and the hook members 12 and 13 to be drawn down firmly upon the upper surface of flanges 5' and results in such flanges being gripped with a tremendous force. In other words, the spring plate member 6 is adapted to grip the flanges of a rail with sufficient force to prevent the movement of the rail relative to the spring plate to resist the slightest movement and the leverage action is adapted to increase the gripping power of the chisel edge 19 and the hooks 12 and 13 upon the flanges for the purpose of resisting additional movement.

Obviously those skilled in the art may make various changes in detail and arrangement of parts without departing from the spirit and scope of the invention defined by the claims hereto appended, and it is therefore desired not to be restricted to the precise construction herein disclosed.

60 65 Having thus fully described and shown an

embodiment of the invention, what is desired to be secured by Letters Patent of the United States is:

1. In combination, a railway rail, a tie under said rail, and a resilient member having end portions engaging the edges of the flange portions of said rail and an edge portion engaging the bottom surface of said flange, said edge portion being beveled at an acute angle to bite into the surface of said rail.

2. In combination, a railway rail, a tie under said rail, a resilient plate disposed under the rail and adjacent the side of said tie, hooks on the ends of said plate for gripping the flange of said rail, and a spheroidal bulge on the side of said plate to cause a spring force to be developed to draw said plate ends towards each other.

3. In combination, a railway rail, a tie under said rail, a resilient plate disposed adjacent the side of said tie and having its intermediate portion curved about an upright axis away from said tie, and means on the edge of said curved portion for digging into the bottom surface of said rail.

4. In combination, a railway rail, a tie under said rail, a resilient plate having a recess therein for receiving the flanges of said rail, said plate being positioned adjacent the side of said tie and curved outwardly about an upright axis away from the tie intermediate the ends of the plate, and an extension on the upper edge of said curved portion having a sharp edge for engaging the bottom surface of the flange of said rail.

5. In combination, a railway rail, a tie under said rail, a resilient plate disposed adjacent said tie having a portion intermediate its ends curved about an axis transverse to the length of said plate away from said tie, and an extension on the upper edge of said curved portion for engaging said rail to provide a fulcrum about which said plate tends to rotate when said rail is moved relative to said tie.

6. In combination, a railway rail, a tie under said rail, and a resilient plate having end portions thereof adjacent said tie and an intermediate portion spaced-apart from said tie and beveled on the side adjacent said tie to form a chisel edge to dig into the bottom of said rail.

7. In combination, a railway rail, a tie under said rail, and a resilient plate having end portions thereof adjacent said tie and an intermediate portion spaced-apart from said tie and having a sharpened edge extending upwardly to engage the bottom of said rail to provide a fulcrum about which said plate is turned when said rail moves relative to said tie.

8. In combination, a railway rail, a tie under said rail, a resilient plate having a

recess therein to receive the flanges of said rail, said plate having a portion intermediate the ends thereof and extending entirely across said plate bowed outwardly 5 away from said tie and an extension on the top edge of said outwardly bowed portion for engaging the bottom of said rail at a point spaced-apart from the side of said tie.

10 9. In combination, a railway rail, a tie under said rail, a resilient plate, hooks at each end of said plate, extending over the flanges of said rail, the bottom of the end portions of said plate engaging said tie, an 15 extension on said plate adapted to engage the bottom of said rail at a point removed from said tie, said extension being adapted to hold the upper portion of said plate ends apart from said tie and to act as a fulcrum 20 when said rail moves relative to said tie for increasing the grip of said hooks upon said rail flange edges, the entire middle portion of said plate being bowed outwardly to 25 form a spring resiliently holding the hooks at the ends of said plate together.

10. In combination, a railway rail, a tie under said rail, a resilient plate having the entire central portion bowed outwardly and having end portions engaging said tie, 30 hooks for engaging the edges of the flanges of said rail, and means on said resilient plate adapted to cause said hooks to bear downwardly on said flanges when said rail moves relative to said tie.

35 11. In combination, a railway rail, a tie under said rail, a resilient plate adjacent said tie, said plate having a bowed portion therein to permit resilient longitudinal extension of said plate, hooks on the end portions of said resilient plate for engaging the edges of said flanges, said hooks being adapted to hold said plate in place on the rail, and means on said plate to cause a leverage to take place clamping said hooks 45 tightly upon said flanges when said rail moves relative to said tie.

12. An anchoring device for railway rails, comprising a resilient plate having a recess therein to receive the flanges of said rail, 50 said plate having the entire center portion bowed to permit resilient longitudinal extension of said plate, hooks for engaging the upper surface of said flanges, and means

for causing said hooks to bear downwardly upon said flanges. 55

13. An anchoring device for railway rails, comprising a resilient plate, a hook at each end of said plate adapted to be forced by the resiliency thereof firmly against the flanges of said rail, and means spaced-apart 60 from the line joining said hooks and extending upwardly against the bottom of said rail to cause said hooks to grip said rail with an additional force when said rail tends to move. 65

14. The combination with a railway tie and a rail supported on said tie, of means for holding said rail against longitudinal movement on said tie, said holding means having portions engaging said rail at longitudinally spaced apart points thereon and having the central portion thereof bowed outwardly and provided with a spheroidal boss thereon to impart longitudinal elasticity to said holding means, and an abutment portion disposed against the tie below the rail so that pressure of said abutment portion against said tie causes the holding means to act as a lever to exert gripping action on said rail. 70 75

15. The combination with a tie and a rail supported thereby, of an anchor plate having opposite ends engaging the flanges of said rail adjacent one side of said tie, said plate extending downwardly below said rail 80 and engaging the side of said tie, the central portion of said plate being curved away from said tie and having a toothed upper edge engaging the lower face of said rail at a point spaced away from said tie and having a spheroidal boss thereon to add resiliency and strength to said central portion. 85

16. The combination with a tie and a rail supported thereon, of an anchor having hooked portions at opposite ends thereof, 90 and a central bend to resiliently draw said hooked portions against opposite edges of the rail flange, said anchor being arranged to engage a face of said tie below said rail while said central bend engages the lower face of said rail at a point spaced from said tie. 95 100

In testimony whereof I have signed my name to this specification on this 27th day of July, A. D. 1925.

ALPHONSO T. PALMER.
